Des. 187,106
Patented Jan. 26, 1960

187,106

TABLE LIGHTER OR SIMILAR ARTICLE

Lawrence David Williams, Sparkbrook, Birmingham England, assignor to Ronson Corporation, Woodbridge, N.J., a corporation of New Jersey

Application July 28, 1959, Serial No. 56,963

Claims priority, application Great Britain
February 17, 1959

Term of patent 14 years

(Cl. D48—27)

FIG. 1.

FIG. 2.

FIG. 3.

FIG. 4.

FIG. 5.

Fig. 1 is a perspective view of a table lighter showing my new design.

Fig. 2 is an elevational view thereof as seen from the opposite side of Fig. 1.

Fig. 3 is an end elevational view of the lighter.

Fig. 4 is a plan view as seen from above of the lighter.

Fig. 5 is a plan view as seen from below of the lighter.

I claim:

The ornamental design for a table lighter or similar article, substantially as shown.
